[57] CLAIM

The ornamental design for an automobile tire, as shown and described.

DESCRIPTION

FIG. 1 is a front view of the automobile tire, showing the new design, the top plan view and the bottom plan view appearing the same as the front view;

FIG. 2 is a rear view of the automobile tire;

FIG. 3 is a right-side view of the automobile tire, the left-side view appearing the same as the right-side view;

FIG. 4 is a fragmentary front view, showing in enlargement the portion of 4—4 in FIG. 1; and,

FIG. 5 is a sectional view, taken in the direction of line 5—5 of FIG. 4.
